UNITED STATES PATENT OFFICE.

EUGENE F. CHAPMAN, OF WILSON, NEBRASKA.

WAGON-BOX..

SPECIFICATION forming part of Letters Patent No. 269,009, dated December 12, 1882.

Application filed July 3, 1882. (No model.)

To all whom it may concern:

Be it known that I, EUGENE F. CHAPMAN, of Wilson, in the county of Colfax and State of Nebraska, have invented certain new and useful Improvements in Wagon-Boxes, of which the following is a full, clear, and exact description.

My invention relates to certain improvements in the end-boards of wagon-boxes, and 10 to the means for attaching them to the box and holding them in place for closing the ends of the box; also to separate side and end boards for enlarging the wagon-box.

Reference is to be had to the accompanying 15 drawings, forming a part of this specification, in which similar letters of reference indicate corresponding parts in all the figures.

Figure 1 is a perspective view of a wagon-box having my improved end-boards attached 20 thereto, the same being held in position for closing the ends of the box. Fig. 2 is a detailed perspective view of the forward end of the box, showing the end-board slightly tipped back. Fig. 3 is a similar view of the rear end 25 of the box, showing in full lines the end-board placed upon the edge of the box, and in dotted lines suspended under the box; and Fig. 4 is a perspective view, showing my improved side and end board for enlarging the box in 30 place.

A represents the wagon-box; B, the forward end-board, and C the rear end-board of the box, and D D' represent the bent rods or bails of iron, by which the boards are attached to 35 the box.

The rear end-board, C, is attached to the bail D' by means of the eye-plates ff, secured to the outside of the end-board near its ends, as 40 shown in Figs. 1 and 3, the eyes f' f' of the said eye-plates being at or near the top or upper edge of the board. When this means of attachment of the end-board to the bail is used for locking the end-board in the end of the box, I prefer to use the sliding spring-bolts i, which 45 are adapted to pass through the holes e in the side plates, g. These bolts are operated by the arms i', secured at right angles to the bolts, and which protrude from the slots e' in the plates h, secured to the outside of the end- 50 board over suitable recesses cut in the board for the reception and movement of the said sliding bolts i.

The forward end-board, B, might be attached to the bail D in the same manner that the rear end-board, C, is attached to the bail D', and locked in the end of the box in the same manner; but I prefer to attach it by means of the cleats E E, secured to the outside of the end board at its ends, as shown in Figs. 1 and 2. These cleats E E are recessed 55 upon their inner surfaces, as shown at a a, so that when secured in place upon the end-board over the bail, channels or ways will be formed in which the bail is adapted to be moved, or for admitting the end-board to be moved upon 60 the bail. When this means of attachment of the end-board to the bail is used for locking the end-board in the box, I provide the box A with the hooks b b, behind which the lower corners of the board are placed, and provide 65 the cleats E E, near the upper ends of the recesses a a, with the bolts or screws c c, which are adapted to reach into the recesses for locking the bail at the upper end of the channels or ways, as shown in Fig. 1. With the bail 70 locked in this elevated position and the lower corners of the board placed behind the hooks b b, the board will be held securely in place, 75 closing the end of the box.

Upon withdrawing the spring-bolts or screws 80 c c the board B may be tipped forward to the inclined position shown in Fig. 2, or it may be swung upward and placed in a horizontal position upon the upper edges of the box and used for a seat, or swung downward under 85 the box and placed upon the hounds or thills of the wagon out of the way. When the board is swung upward and placed upon the box for a seat it will be observed that the outside of 90 the board will be uppermost, and will thus always present a clean surface.

The rear end-board, C, when the bolts i are withdrawn from the holes e, may be dropped down to the position shown in dotted lines in 95 Fig. 3, out of the way; or it may be swung outward and upward and placed in a horizontal position upon the upper edges of the box, as shown in full lines in Fig. 3, and used as a seat.

Instead of attaching the rear end-board, C, to the bail D', as shown and described, by 100 means of the eye-plates ff, the same might be attached in the same manner that the forward board, B, is attached to the bail D, so that both will be alike; but the plan shown is pre-

ferred, since the forward board may be extended upward, as shown, to form a dash-board to the box when the side and end boards for enlarging the box are not used. When these are used for enlarging the box the upward extension serves as the forward end-gate, as will be understood from Fig. 4.

G G are the separate side-boards for enlarging the box, and H is the separate rear end-gate of the extension. The end-gate H is provided with the hooked plates l l, which are adapted to hook under the bail D', and is formed with the projections m m, and provided at or near its upper edge with the bent and hooked rod K, the hook portions k k of which are adapted to be hooked in the eyes or staples n n in the side-boards G G, as shown in Fig. 4. The side-boards G G are provided upon opposite sides with fixed standards or cleats q s, which reach down over the inner and outer faces of sides A to hold boards G thereon, said boards G being provided at their forward ends with the hooks t t, which are adapted to hook into the eyes or staples t' t', secured to or driven into the outside of the cleats E E of the front end-board of the box. At the rear end the said side-boards G G are formed with the extensions m' m', which, when the boards are in place upon the main part of the box, fit under the projections m m of the end-gate H, which firmly locks the said side boards in place, as shown in Fig. 4. By this means the side and end boards may be quickly and easily put in place for enlarging the box and as quickly and easily removed, and when in place they are held as firm and strong as the main part of the box.

Having thus fully described my invention, I claim as new and desire to secure by Letters Patent—

1. The bail D', hinged to the sides of the box, in combination with the end-board C, attached thereto by the eye-plates f f, and provided with the sliding bolts and catches i i, substantially as described.

2. The combination, with the box A, having the end-boards C secured thereto by the bail D', of the separate side-boards G G, and the end-gate H, provided with the hooked plates l l, substantially as described.

3. The end-gate H, having the hooked plates l l and hooks k k, in combination with the side-boards G G and bail D', substantially as and for the purposes set forth.

4. The end-gate H, formed with the projections m m, in combination with the side-boards G G, provided with the projections m' m', substantially as and for the purposes set forth.

5. The side-boards G G, provided with the standards or cleats q and outside cleats, s, and having the hooks t t at their forward ends, in combination with the end-gate H, provided with the hooked plates l l and hooks k k, the ends of the said gate being formed with the projections m m, and the rear ends of the side-boards being formed with the projections m' m', and having the staples n n, substantially as described.

EUGENE F. CHAPMAN.
